UNITED STATES PATENT OFFICE.

AUGUSTIN L. J. QUENEAU, OF SOUTH BETHLEHEM, PENNSYLVANIA.

METHOD OF CHARGING RETORTS, MUFFLES, FURNACES, AND THE LIKE.

No. 813,021.

Specification of Letters Patent.

Patented Feb. 20, 1906.

Application filed January 16, 1905. Serial No. 241,272.

To all whom it may concern:

Be it known that I, AUGUSTIN L. J. QUENEAU, a citizen of the Republic of France, residing at South Bethlehem, county of Northampton, State of Pennsylvania, have invented certain new and useful Improvements in Methods of Charging or Feeding Retorts, Muffles, Furnaces, and the Like; and I do hereby declare the following to be a full, clear, and exact description of the invention, such as will enable others skilled in the art to which it appertains to make and use the same.

My invention relates to certain new and useful improvements in the method of charging retorts, muffles, and the like, and in the method of feeding pulverized fuel to steam-boiler furnaces, rotary cement-kilns, and other furnaces, wherein it is desirable to impart to the entering body of pulverized fuel a long trajectory.

Prominent among the useful applications of my improved method is its applicability to the metallurgy of spelter, wherein the ingredients of the charge to be supplied to the retorts or muffles of the furnace-bench are in the present practice shoveled into the open ends of the retorts or muffles by hand. The workmen employed for this purpose receive the wages of highly-skilled labor. The work of charging the retorts by hand in view of the small cross-sectional area of the retorts and the size of the charging-openings and in view of the heat of the furnace and the fumes constantly issuing from the condensers is of a very trying character, so that in spite of the endurance of the furnacemen and the skill, care, and attention which they give to their duties it frequently happens that there is great inequality in the charging of the retorts of the same bench, so that in some instances the charge of certain of the retorts or muffles is found to be completely worked out or exhausted long before others of the same series have completed their operation. The inequality of the hand-charging procedure is particularly manifest at certain seasons of the year and under certain adverse climatic conditions, and especially during the late hours of the night and near the end of a shift, at which time the energy of the furnacemen flags. The losses resulting from the varying

and uneven hand-charging procedure are serious in amount and materially cut down the efficiency and working value of the plant. 55

The purpose of my invention is to substitute for the uncertain and uneven charging method referred to a method of charging which is absolutely reliable under all conditions of time and climate, weather and temperature, and which is uniform and continuous and of such a character that it may be applied even by unskilled labor to the successful charging of retorts and muffles of small cross-section or which have small 65 charging apertures. Its characteristic feature consists in projecting the retort or furnace charge by an impact blow into the retort, muffle, or furnace in a continuous and homogeneous stream, which is preferably 70 caused to assume a substantially cylindrical form after it has received its initial momentum and is under way. Where the ingredients of the charge are different substances associated together for the production of 75 some particular reaction—as, for instance, the zinciferous materials and fine coal of a zinc-muffle charge—the impact blows are preferably so delivered as to further comminute and more intimately intermingle the associated 80 elements of the mixture, thereby lessening the attention that need be given to the preliminary mixing of the charge and making it much more satisfactory than can usually be expected from hand-mixing. 85

In the accompanying drawings I have illustrated a convenient form of apparatus for carrying my improved method into effect, although it will of course be recognized that it is not dependent upon the employment 90 of any particular form of apparatus to realize its advantages.

In the apparatus shown in the drawings, Figures 1, 2, and 3 represent, respectively, a top plan view, side elevation, and rear elevation of a charging-machine embodying my improvements. Fig. 4 represents a front elevation, partly in section.

Referring to the drawings, it will be noted that, as shown, the casing of the machine is made up of a base casting A and a top casting B, said castings being provided with projecting flanges for bolting them together. Between the two castings is journaled the

shaft C, adapted to be revolved by the drive-pulley D and provided with suitable brasses and lubricating devices.

Upon the shaft C is keyed the impeller-disk, consisting, preferably, of a single casting having a hub portion *a* with end flanges *b*, a flat main body portion constituting a circular plate of a diameter corresponding to the internal diameter of the casing, and a series of blades *c* of a curvature, indicated in Fig. 2. At their outer ends these blades *c* are of a width corresponding to the width of the casing and then continue of this width to a radial distance corresponding to the lower portion of the feed-inlet E, from which point they decrease in width until they merge into the surface of the disk. It will be apparent, therefore, that any material forced into the casing through the inlet-opening E will receive the full impact blow of the extreme outer portion of the blade approaching at that particular instant and dropping in front of the widest and outmost portion of the blade and at right angles thereto will have imparted to it a momentum equivalent to that due to a sharp blow, in consequence whereof the material receiving such impact blow will be driven out tangentially through the upwardly-inclined outlet-spout F and its auxiliary pipe-section F'.

The function of the pipe-section F' (see Fig. 2) is to give form and direction to the issuing stream of charging material, and in this regard the pipe-section F' acts in a measure like the barrel of a gun to insure against scattering of the projected particles. In some instances I may, if desired, substitute for the single pipe-section F' a forked pipe-section, so as to simultaneously charge two or more vessels at one and the same time.

In practice the material supplied to the charging-machine will be fed from a suitable hopper into the inlet-opening E by means of a feed-screw G, delivering into a pipe E', bolted to the inlet-pipe E, so that the charging-machine will be thus supplied with a forced feed, which may be so regulated as to correspond exactly to the conditions of use, and particularly to the speed of revolution desired.

The speed of revolution of the impeller-disk and the speed of revolution of the conveyer-screw are so adjusted with respect to each other as to furnish a resultant stream of material corresponding to the particular requirements of use. In practice I have been enabled to produce a stream of material which, shot through the outlet, travels in a straight path without any material spreading for a distance varying from three to ten feet and more, this charge moving in a practically solid, homogeneous column of generally

cylindrical form, so that it can be directed into a retort or muffle opening of a correspondingly small diameter. The obtaining of this non-spreading, solid, and homogeneous column is due in great measure to the fact that the casing is sealed at all times by the material fed into it, so that practically no air can enter with the material into the casing. By reference to Fig. 4 it will be noted that the feed-screw G for supplying the material from the hopper to the inlet-pipe terminates in advance of the discharge-mouth of the inlet, thereby leaving an intervening portion which is constantly packed full of the material and which remains full, whether the feed-screw is in operation or not. There is therefore no indraft of air into the casing, and the column of material which issues through the tangential discharge-spout is practically devoid of air. If air were present as an element of the column projected from the tangential discharge-spout, it would tend to expand and scatter the material on its way to the retorts, and the air within the retorts would itself oppose such resistance to the entrance of a column of material containing air that additional scattering would take place at the retort-mouths, thereby preventing the effective charging of the comminuted material. By the expedient of sealing the casing against the entrance of air with the material supplied thereto both of these disadvantages are overcome.

I do not claim herein the particular charging-machine shown, for the reason that I have made said charging-machine the subject of a separate application for Letters Patent, Serial No. 241,273, filed January 16, 1905.

What I claim is—

1. The method of supplying retorts, muffles, furnaces, and the like, with finely-divided solid ingredients, which consists in projecting the same, by impact blows, in a continuous and homogeneous stream, into the retort, muffle, or furnace; substantially as described.

2. The method of supplying retorts, muffles, and the like, with a charge of associated ingredients, which consists in projecting the charge, by impact blows, in a continuous and homogeneous stream into the retort or muffle to be charged, said impact blows being of a character to further comminute and intermingle the ingredients; substantially as described.

3. The method of supplying retorts, muffles, furnaces, and the like, with finely-divided ingredients, which consists in projecting the same in a continuous and homogeneous stream into the retort, muffle, or furnace, avoiding subsequent scattering of the stream by practically excluding air from it during its

formation, and consolidating said stream into a substantially cylindrical column after it has received its initial momentum and is under way; substantially as described.

5 4. The method of supplying retorts, muffles, furnaces and the like, with finely-divided solid ingredients, which consists in projecting the same, by impact blows, in a continuous and homogeneous stream, into the

retort, muffle, or furnace, and practically excluding air from said stream; substantially as described.

In testimony whereof I affix my signature in presence of two witnesses.

AUGUSTIN L. J. QUENEAU
